SUBMARINE TOY

Stanley H. Gordon, 7679 N. Rogers Ave., Chicago, Ill.
Filed Aug. 15, 1958, Ser. No. 755,196
7 Claims. (Cl. 46—243)

This invention relates to improvements in motor driven nautical toys and more particularly to toys designed to operate intermittently on and under the surface of the water.

One of the problems of such toys is that of water leaking into the hull compartments containing the motor and other elements which can be damaged within a short time.

Any water getting into the hull compartment upsets the balance and buoyancy of the toy and can stop its operation or cause it to sink, since to facilitate under water operation, diving toys are designed with minimum buoyancy.

It is relatively easy to provide a watertight seal at points in the hull or body where access is required, because stationary parts are secured together; for example a removable cover to change batteries; but sealing the rotatable propeller shaft in the hull or propeller shaft tube by a conventional seal is quite difficult in toys. In previous water toys driven by flea-power motors the friction caused by conventional seals greatly reduces the propeller speed and causes a heavy drain on the power supply without useful work being performed. Also, the seals used in such toys tend to leak after a short time due to evaporation of the oil in the seal packing, wear, or seal shrinkage.

An alternative to a seal is to enclose the propeller shaft in a tube. An inclined tube is sealed to the hull, and generally the tube is inclined downwardly from the motor and out through the hull. The propeller shaft runs freely in the tube, and the water rises inside the tube only as far as the air pressure inside the hull permits. This arrangement has several disadvantages however, one of which is the limitation as to buoyancy space in the hull exposed to the tube. If it is too large a space, water from the tube will enter the hull. Another disadvantage is that the propeller operates at an angle to the direction of the motion of the hull, and thus loses efficiency for forward movement and at the expense of good performance. Also, the motor must be either mounted at an angle, or connected to the propeller shaft by a universal joint such as a spring, which reduces the efficiency of the drive train. The chief disadvantage however with the tube arrangement, as far as the present invention is concerned, would be that when the toy is inverted in the water by the user, water freely enters the hull, and diving toys would be quickly filled with water due to rapidly increasing water pressures.

In addition to the problem of preventing the entry of water into the motor and other parts of the toy, previous toys lack the realistic action of repeatedly diving and surfacing; operating intermittently; and reversing directions.

This singular type of operation provokes a strikingly realistic action in a toy whale, alligator, submarine or the like, since the toy appears to be intelligently responsive to life conditions under which such actions would be performed.

Moreover, prior to this invention the power supply has been quickly exhausted by the requirement for the continuous use of power while the toy is in operation. With the present invention, idleness is provided for realism and also to save power. Not only is idleness used advantageously, but operation forwardly and reversely more than doubles the useful operating time and entertainment value of the toy.

2

One of the objects of the present invention is to provide a nautical toy having a motor compartment completely and permanently watertight so as to eliminate the necessity of and difficulties experienced with a propeller shaft tube or a propeller shaft seal.

The invention is also characterized by a novel performance pattern of natural actions and operational sequences generally encountered with intelligent controls, so that nautical toys can be made to dive and surface repeatedly, with the motor starting and stopping or reversing automatically while in operation to produce the continuous diving and surfacing action.

A further object of this invention is to provide in a nautical toy intermittent motor operation in order to greatly reduce the drain on the power supply.

Still another object of this invention is to utilize a time delay switch which controls the descent and the action of the toy.

Another object is to provide a toy which is inexpensive to manufacture and maintain, is rugged in construction and life-like in performance.

These being among the objects of this invention, other and further objects will be apparent from the description and drawings relating thereto in which:

25 FIG. 1 is a side elevational view of the preferred embodiment of the invention, a submarine, showing a control switch in phantom;

FIG. 2 is a top view of the embodiment shown in FIG. 1;

30 FIG. 3 is a cross-sectional view of the lower half of the hull of the submarine, showing the control switch in cross-section;

FIG. 4 is a side elevation of a submarine conning tower in which an alternative control switch of a float type is disclosed; and

35 FIG. 5 is a side elevation of a submarine conning tower in which an alternative control switch of pressure sensitive, surface sensing type is used.

In order to accomplish the objects stated, an embodiment of the present invention is disclosed herein in the form of a toy submarine having a buoyant hull, dive planes, rudder, and rear horizontal stabilizing planes, as found with real submarines. A watertight hatch provides the access required for changing the power source,

40 such as a battery. A periscope is rotatably mounted on the conning tower of the hull, and the periscope shaft is attached to a rotary on-off switch in the conning tower. There is preferably a single propeller at the stern, attached to a propeller shaft journalled in the hull. The battery and an electric motor are mounted inside an air sealed compartment in the hull. The motor shaft preferably is not mechanically attached to the propeller shaft, but drives it by means of magnetic flux. The magnets of this drive are spaced and separated by a thin, non-magnetic wall which completely seals the motor compartment from the water, while the propeller shaft compartment is open to the water, preferably in a way that when the toy is placed in the water, air is trapped and when the propeller starts a trail of bubbles is left behind

45 the submarine as it moves forwardly and submerges.

50 Inside the keel, the motor control time delay switch preferably comprises a sealed tube mounted on an incline, having the lowest portion aft. Two contacts are sealed into the lower end of the tube and the tube contains a quantity of mercury. The sides of the tube are so constructed as to delay the flow of mercury from one end to the other, providing the time delay feature of the switch.

55 A second embodiment of the invention is identical to the first except for the use of a different type of time delay switch consisting of an arrangement in which buoyancy is employed. The time delay switch is contained

in a compartment in the conning tower which floods and empties as the submarine dives and surfaces. The time delay switch comprises a float mounted on an arm pivoted so as to allow the float to rise and fall as the water level in the compartment rises and falls. The bottom of the float contains a contact bar which seats between the contact points. Two holes regulate the flooding and emptying of the conning tower compartment.

A third embodiment of the invention is identical to the first except for the use of a pressure sensitive, surface sensing switch. A conning tower compartment containing a float actuated switch is open to the water only at the bottom. Water enters through a one-way check valve as the submarine depth increases. At a pre-set depth enough water has entered to lift the float to break electrical contact. The submarine then surfaces but the water in the compartment is retained by a second ball valve float, which does not lower the compartment water level until the submarine has surfaced. Then the ball float drops away from sealing position allowing the compartment water to escape and the contact float makes electrical contact again.

Still another embodiment of the invention is identical to the first except for the use of a thermal switch in the motor circuit to regularly start and stop the motor.

An additional embodiment of the invention is an additional switching arrangement added to any or all of the previous embodiments. It includes a two position, double pole double throw switch linked to a movably mounted rod which extends beyond both ends of the hull. When the toy drives either end of this rod against a solid object, it operates the switch, reversing the motor.

So that the present invention may be more clearly understood applicant now refers to the drawings in which:

The hull 10 is constructed of metal, plastic, or other suitable material. It is designed to float in water in a horizontal attitude, about nine-tenths submerged. It contains two compartments, one floodable 11, the other permanently sealed 12. Attached to the hull at the stern, beneath waterline, are two horizontal stabilizers 13. These are constructed of the same material as the hull and are fixedly mounted coplanar to each other. A vertical steering rudder 14, comprising a thin flat sheet of the same material as the hull, having the leading edge rolled to define a tubular portion 15, is mounted pivotally at the stern by a rudder mounting pintle wire 16 extending into the aforesaid tubular portion.

The axis of the rudder is preferably inclined as shown in FIG. 1 to inwardly heel the hull when coming about. At the bow of the submarine, attached to each side of the hull below the waterline, are dive planes 17. These thin flat vanes are made of the hull material and are each attached to the hull by respective ball and socket joints 18, so that they are adjustable to any dive angle desired. The conning tower 20 of like material is attached to the hull and contains a periscope which operates an on-off switch 22.

The propeller 23 is soldered to the propeller shaft 24, which is journaled within the hull in the floodable compartment 11. A magnet drive consisting of a primary drive magnet 28 and a secondary drive magnet 30, separated by a thin non-magnetic sealing wall 32, conveys power from the motor 34 to the propeller shaft in a one-to-one ratio. The primary drive magnet 28 is attached to the end of the motor armature shaft 36 by a rubber fitting (not shown), and the secondary drive magnet 30 is attached to the forward end of the propeller shaft 24 by an identical fitting. The motor is rigidly supported in the hull by a cross member 40. A battery 42 is mounted between contact points 44 and 46 and the battery may be removed by opening the waterproof hatch 48. Below the battery is the gravity actuated time delay switch 50, comprised of a sealed tube 52 mounted on an incline with the upper end toward the bow. Two electrical contact wires 54 enter the lower end of the tube,

and a quantity of mercury 56 in the tube provides an electrical contact whenever it is present in the lower end of the tube. The mercury travels the length of the tube in response to gravity as the tube attitude changes during the diving and surfacing of the submarine. At either end of the tube there is an enlargement of the inside tube diameter 58. When the tube inclines downward from the mercury-filled end, the mercury is momentarily retained by an air trap formed by this enlargement. The purpose of this is to delay the action of the mercury as by a dash pot action for a moment at a given incline of the tube, but not to stop it. Along the sides of the tube are projections 60 which further impede the progress of the mercury from one end of the tube to the other, without stopping it.

Another principle of self-acting time delay switching for a diving water toy is shown in FIG. 4 as a switch mounted in a float compartment 61 of the conning tower of a submarine. A float 62 is mounted on an arm 64 pivoted at 66 so as to allow the float to rise and fall. The bottom of the float contains a contact bar 68 which seats between the contact points 70. Two holes, 72 and 74, regulate the flooding and emptying of the conning tower. When the conning tower is empty the contact is closed, starting the motor, and the submarine dives. In a predetermined time after the submarine dives, the conning tower fills with water, raising the float and breaking the contact. The contact will close again after the submarine has surfaced and water has drained from the conning tower, lowering the float contact bar to the contact points again, to restart the motor.

Still another principle of switching is the pressure sensitive, surface sensing switch shown in FIG. 5. The compartment 77 contains a float 76 mounted on a float arm 78 which is pivoted 80 so that the rise and fall of float 76 will make and break the electrical contacts 82. A drain hole 84 is kept closed by the valve float 86 whenever it is submerged, but when the water level is lower than the drain hole 84, as when the submarine has surfaced, the hole is open and the float is retained in proximity to the drain hole 84 by a retaining pin 88. A one-way valve comprising a valve hole 90, a ball 92, and a ball retaining pin 94, allows water to enter but not to escape.

Another principle of switching (not shown) is an electrical thermal switch which can be placed in the motor circuit. Such a switch would operate regularly to start and stop the motor.

Another means (not shown) for reversing the motor may be provided by a two position, double pole double throw switch which is mechanically linked to a rod, the ends of which project outwardly from the bow and stern of the hull. Upon striking any solid object, the rod would operate the switch, reversing the polarity of the motor circuit.

The submarine embodying a modification of the gravity actuated, time delay switch operates as follows. On the surface of the water, the submarine floats in a horizontal position, nine-tenths submerged. The propeller shaft compartment is flooded, but the non-magnetic sealing wall hermetically seals the motor compartment against the water. The propeller, rudder, stabilizing planes and dive planes are submerged. The mercury in the tube is resting on the contact points to close the motor circuit. With the periscope switch turned on, the motor operates to drive the primary drive magnet, which is spaced close to but not touching the non-magnetic sealing wall. The magnetic flux of this magnet penetrates the wall and drives the secondary drive magnet mounted on the propeller shaft, which rotates the shaft in its journals to drive the propeller. The propeller drives the submarine forward but also creates torque which attempts to rotate the submarine around its longitudinal axis. However, the low center of gravity and the control surfaces effectively resist this force. If the leading edges of the dive planes are above

horizontal, the submarine will continue to run on the surface. If they are slightly below the surface the submarine will begin a long shallow dive, and the dive angle will steadily increase. At a predetermined angle the mercury tube is tilted so that the mercury in the tube will attempt to roll from the contact points. The air trap formed by the bulb 58 will detain the mercury a few seconds, and then the mercury will start to descend to the bow end of the tube. The projections on both sides of the mercury impede its flow but do not stop it. The contacts are now open and the motor stops. The submarine continues to glide downward for a moment but its natural buoyancy compels it to rise and as it begins to do so, still gliding forward, the rear stabilizing planes offer more resistance to the rising motion than do the smaller bow planes, with the result that the bow slowly lifts, bringing the glide path of the submarine in a long curve toward the surface. When the bow has risen to horizontal the mercury, now at the forward end of the tube attempts to return to the contact end, but the air trap holds it and the bow continues to rise. Freeing itself of the air trap, the mercury is impeded in its rearward travel back toward the stern by the projections on both sides of the tube, allowing the bow to rise still further. Finally the mercury returns to the contact points, starting the motor. The submarine is driven the rest of the way to the surface under power, breaking the surface at a speed much faster than normal, due to the assistance of buoyancy, and immediately it begins another dive.

Varying the angle of the dive planes further down from horizontal causes the submarine to dive more quickly and steeply, and to attain the cut-off angle rapidly. In such a case the submarine may surface while still gliding, and then turn itself on while on the surface.

In a submarine having the floating contact in a floodable compartment, the submarine will dive at whatever angle the dive planes determine, and continue to dive until the float compartment floods sufficiently to lift the float contact bar from the contacts. The submarine will then glide to the surface and remain there until the float compartment drains, letting the float contact bar back down on the contact points, restarting the motor.

In a submarine having the pressure sensitive, surface sensing switch, the submarine will dive to a predetermined depth at which point sufficient water will be forced into the floodable compartment through the one-way valve to lift the float, breaking the circuit. The water is prevented from leaving the compartment by the one-way valve and also by a valve float, until the submarine glides to the surface. The valve float then releases the water in the compartment, allowing the contact float to drop, restarting the motor.

In a submarine having a thermal switch, the motor would start, operate for a predetermined time, and then stop, and remain stopped for a predetermined time, and then restart. The submarine would dive while the motor ran, and resurface while the motor was stopped.

In a submarine or other toy for use in water, having a two position double pole double throw switch linked to a movably mounted rod projecting outwardly from both ends of the hull, the motor is reversed every time the bow or stern of the toy strikes a solid object. If this switch were used in combination with any of the previously mentioned switches, it would add to their operation this impact reversing feature.

Having thus described one embodiment of the invention and several of its alternatives, it is to be understood that the mechanism of this structure may be applied to other structures or altered without departing from the spirit and scope of the invention which are commensurate to the appended claims.

What is claimed is:

1. A buoyant toy for use in water comprising a hull having diving and steering control surfaces, a motor in

said hull, means operated by said motor for propelling the hull, gravity responsive means for starting and stopping and reversing said motor, operative when the fore and aft attitude of the hull deviates a predetermined distance from the horizontal said gravity responsive means comprising an element movable between two predetermined limits, delay means for delaying the travel of said element between said limits, said delay means comprising physical projections in the path of travel of said element, said projections being permanently affixed in said path of travel to deflect and retard the movement of said moving element in either direction between said two predetermined limits.

2. The combination called for in claim 1 in which the last means includes a tube mounted in the hull and normally inclined downwardly at the rear, electrical switch contacts mounted at the ends of said tube, and a mobile mass of mercury in said tube of a height less than the vertical clearance in the tube when the mercury is located at a point in the tube intermediate its ends.

3. The combination called for in claim 1 in which said gravity responsive means includes a tube mounted in the hull nad normally inclined downwardly at the rear, electrical switch contacts mounted at the ends of the tube, projections along both interior sides of said tube, and a mobile, electrically conductive bearing of a size smaller than the inside diameter of said tube and smaller than the space between said projections.

4. A buoyant toy for use in water comprising a hull having driving and steering control surfaces, a motor in said hull, means operated by said motor for propelling said hull, a floodable compartment within said hull and above the waterline of said hull, said compartment being partially open at the upper part of said compartment, whereby in the diving and surfacing of said hull said compartment floods and empties in a predetermined time and buoyant means within said compartment responsive to the water level within said compartment whereby electrical contact is established when said buoyant means is unsupported by water in said compartment.

5. A combination called for in claim 4 in which the buoyant means for starting and stopping said motor includes a floodable compartment above the waterline of said hull, said compartment having holes restricting the passage of water both into and out of said compartment so as to delay both the flooding and the emptying of said compartment at a predetermined rate, a mobile float within said compartment, electrical contacts controlled by said float member to make the circuit when said float member falls in response to a change of water level in said floodable compartment.

6. A buoyant toy for use in water comprising a hull having driving and steering control surfaces, a motor in said hull, and a time delay switch for repeatedly starting and stopping said motor in response to a predetermined deviation from the horizontal of the fore and aft attitude of the hull, said time delay switch including a gravity responsive element movable between first and second positions, means for temporarily delaying means comprising the closed ends of a tube receiving said element at each position and temporarily delaying said element by a vacuum formed therewith.

7. A buoyant toy for use in water comprising a hull having driving and steering control surfaces, a motor in said hull, means operated by said motor for propelling said hull, and pressure sensitive means for starting and stopping said motor, operative when said hull submarges or surfaces, said sensitive means including a compartment having a one-way valve for admittance of water, a float sealed water exit valve open when said valve is above water level, a mobile float member within said compartment, electrical contacts controlled by said float member to make contact when said float falls in re-

sponse to a change of water level in said floodable compartment.
